UNITED STATES PATENT OFFICE.

RICHARD P. SIMMONS, OF NEW YORK, N. Y.

WELL-PUMPING APPARATUS.

REISSUED

Application filed August 16, 1927. Serial No. 213,381.

This invention relates to improvements in well pumping apparatus.

The primary object of the invention resides in an apparatus for increasing the flow of oil from oil wells where the pressure behind the oil is insufficient to produce a strong and steady flow at the surface. In some instances, oil wells which contain large quantities of oil cannot be worked as the force or pressure behind the same is insufficient to lift a column of oil to the surface, although the pressure may be capable of lifting the oil a part of the distance.

Another object of the invention is to provide a well pumping apparatus which includes a series of pumps arranged at suitable spaced intervals along the depth of a well from the bottom upward, each serving to lift the column of oil upward to the next higher pump until the oil flows free at the mouth of the well.

A further object is the provision of a series of pumps which are lowered in a well and supported at spaced intervals for lifting oil therefrom, in conjunction with compressed air which is forced into the oil discharge pipe at suitable intervals.

A still further object is to provide an apparatus for increasing the capacity of a well by increasing the natural pressure behind the oil.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a vertical sectional view through an oil well with my improved apparatus therein.

Figure 2 is an enlarged vertical sectional view through one of the pump units.

Figure 3 is a horizontal sectional view on the line 3—3 of Figure 1.

Figure 4 is a similar view on the line 4—4 of Figure 1.

Figure 5 is a similar view on the line 5—5 of Figure 1.

Figure 6 is a vertical sectional view through a well showing a slightly modified form of pumping unit.

Figure 7 is an enlarged vertical sectional view through the lowermost pump unit.

Referring more particularly to the draw-

ings, the reference numeral 10 designates the shaft of an oil well which leads from the basin or head 11 to the surface of the earth. Disposed within the shaft and extending the entire length thereof are shell sections 12 of suitable lengths which have their meeting ends externally threaded for threading engagement with couplings or collars 13. The shaft of the well is bored larger in diameter than the shell sections to accommodate the collars 13 which causes the shell sections to be disposed in spaced relation to the walls of the shaft. My improved pumping apparatus is contained within the shell members which form a wall for the well shaft for preventing the walls from caving in and also prevents dirt and rock from coming in contact with the working parts of the pumping apparatus. The apparatus includes a lower pump unit 14 which is disposed at the bottom of the shaft where it is immersed in the oil below the normal level thereof while pump units 15 are arranged upward within the casing at suitable spaced intervals, as for instance one thousand feet apart. The number of pump units necessary will of course depend upon the depth of the particular well and the amount of natural pressure behind the oil.

Extending downward into the casing from the surface of the earth is a driving rotatable tubular shaft 16 which passes through the top header 17 of the casing 18 of the top pump unit 15 and which co-acts with a bearing 19 for the lower end of the shaft for providing bearings therefor. All of the pump units are driven by the power taken from the driving shaft 16 and each pump unit includes a counter-shaft 20 mounted in bearings 21 extending inward from the walls of the casing 18, and which counter shaft has gears 22 and 23 fixed thereon. The gear 22 of each unit meshes with a gear 24 fixed to the top end of a rotating shaft 25 which extends through the casing 26 of a rotary pump 27. The pump 27 of each unit is of the type known as the "Quimby pump" which includes a right hand screw 28 and a left hand screw 29 provided on the shaft 25, the inner ends of the screws being spaced from each other at a point adjacent the discharge opening 30. The screws on the shaft 25 mesh with opposite pitch screws 31 and 32 provided on a counter shaft 33 journaled in the top and bottom walls of the casing 18. Power is transmitted from the shaft 25 to the counter shaft 33 by co-acting gears 34 and 35 re-

spectively whereby the shafts turn in opposite directions to force oil from the outer ends of the screws toward the discharge opening 28. Each pump has an inlet 34 which 5 communicates with the outer ends of the screws which picks up the oil and forces out through the discharge 28 under pressure.

For the purpose of transmitting the power from one pump to the next lower adjacent 10 pump, I provide the lower end of each shaft 23 with a gear 34 which meshes with a gear 35 on a counter shaft 36. The uppermost pump unit derives its power from the power shaft 14 through a gear 37 fixed to the power 15 shaft but all pump units below receive their power through a tubular counter shaft 38 journaled in bearings 39 and in the headers 15 of the adjacent pump units. The shaft 38 has a gear 40 which meshes with the gear 20 20 41 on the counter shaft 36, and a gear 42 which meshes with the gear 20 of the next lower unit, which drives the next lower pump unit through its shaft 18, and meshing gears 21 and 22.

25 The discharge opening 28 of one pump is connected to the inlet side of the next upper adjacent pump by discharge pipes 43, while the discharge side of the uppermost pump has a pipe 44 connected thereto which 30 rises to the surface of the well and from which the oil is led off to the usual containers.

The lower end of the casing 16 of the pump unit A is reduced in diameter to snugly house the same and the inlet pipe 34 of the same has 35 openings 45 therein through which the oil from the basin is taken in. The lowermost shell section 12 is also slightly different than the other shell sections as the same has its inner wall provided with a number of flat surfaces 46 shown best in cross section in Figure 40 5 of the drawings. The upper end of the casing 16 of the lowermost pump unit has its side walls provided with flat surfaces 47 corresponding in number to the flat surfaces on 45 the shell section to prevent any possible rotation of the pump unit with respect to the shell section.

From the description thus far, it will be seen that upon rotation of the power shaft 50 14, simultaneous rotation will be imparted to the pumps, causing the lowermost pump to lift the oil from the basin to the next higher pump from where it is lifted consecutively to the next higher pumps until it is discharged at the surface of the well. In certain wells, where the pressure is sufficient to lift a slow column of oil, my apparatus will tend to increase the flow, but in other wells, even the pumping apparatus so far described may 55 not be capable of bringing the oil to the surface. In such case, I pass compressed air through the tubular driven shaft 14 which is joined to the hollow counter shafts 38 through pipe connections 46 so as to provide a continuous air pipe down through the well to 60 65

the lowermost pump unit A. The compressed air pipe is tapped into the discharge pipe 43 of each unit adjacent the outlet opening 28 therein through an elbow 48 in each of which a check valve 49 is provided for preventing 70 the oil from entering the air line should the pressure therein drop below the pressure in the oil line. By introducing compressed air in the oil line at every pumping station or unit, I am able to assist the pumps in lifting 75 the oil to the surface and which under any condition tends to increase the production of the well.

In Figures 6 and 7 of the drawings, I have shown a slight modified construction of my 80 invention and in which like reference characters referred to in the preferred form designate like parts. In this form, each pump receives its own power from a separate source of power rather than by a common source as 85 hereinbefore mentioned. The shaft 23 of each pump is operatively connected to an electric motor 50. In lieu of the air pipes shown in the preferred form, I pass a flexible hose 51 down into the well casing and tap in 90 therefrom to the discharge pipes 43 above the respective units. Aside from these differences, the construction is identical to that of the preferred form.

While I have described what I deem to be 95 the most desirable embodiment of my invention, it is obvious that many of the details may be varied without in any way departing from the spirit of my invention, and I therefore do not limit myself to the exact details 100 of construction herein set forth nor to anything less than the whole of my invention limited only by the appended claims.

What is claimed as new is:—

1. In a well pumping apparatus, a plurality of pump units adapted to be arranged in spaced relation within a well, each of said pump units including a casing, driven rotatable screws within said casing, inlets in said casing at the outer ends of said screws, an outlet in said casing intermediate the ends of said screws, discharge piping connecting the outlet of one pump unit with the inlet of the next higher pump unit and with the outlet of the uppermost unit with the surface of a well, transmission means between the driven screws of the respective pumps for simultaneously operating all of said pumps in unison, and a compressed air line tapped into said discharge piping at suitable points therealong for assisting said screws in lifting the pumped fluid through said piping.

2. In a well pumping apparatus, a plurality of spaced pump units, one above the other, each of said pump units including a casing closed at opposite ends, a driven rotatable hollow shaft extending into the top end wall of the uppermost pump unit, a rotary pump contained within said casing having an inlet and an outlet, oil discharge piping connecting 120 125 130

- the outlet of one pump unit with the inlet of the next higher pump unit, a hollow rotatable shaft journalled in the end walls of each adjacent pair of pump units, stationary pipes 5 between the hollow shafts for providing a compressed air conduit, transmission means between the shafts and the respective pumps, and pipe taps connecting the compressed air conduit with said oil discharge piping.
10. 3. In a well pumping apparatus, a plurality of spaced pump units one above the other, each of said pump units including a casing closed at opposite ends, a driven rotatable hollow shaft extending into the top end wall 15 of the uppermost pump unit, a rotary pump contained within said casing having an inlet and an outlet, oil discharge piping connect-
- ing the outlet of one pump unit with the inlet of the next higher pump unit, a hollow rotatable shaft journalled in the end walls of each 20 adjacent pair of pump units, stationary pipes between the hollow shafts for providing a compressed air conduit, transmission means between the shafts and the respective pumps, and pipe taps connecting the compressed air 25 conduit with said oil discharge piping, and check valve within said pipe taps for closing communication therethrough when the pressure of oil in said discharge piping drops below the air pressure in said compressed air 30 conduit.

In testimony whereof I have affixed my signature.

RICHARD P. SIMMONS.
